CLAIM

The ornamental design for a container holder, as shown and described.

DESCRIPTION

FIG. 1 is a top, front, right-side, perspective view of a container holder;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top elevation view thereof;

FIG. 7 is a bottom plan view thereof;

FIG. 8 is a perspective view of the container holder, shown in use with multiple container holders connected together; and,

FIG. 9 is a perspective view of the container holder, shown in use with environment.

In the drawings, the broken lines are for the purpose of illustrating environment only and form no part of the claimed design.

1 Claim, 9 Drawing Sheets
